F. MANKEY.

PANEL.

No. 17,115.

Patented Feb. 15, 1887.

UNITED STATES PATENT OFFICE.

FREDERICK MANKEY, OF WILLIAMSPORT, PENNSYLVANIA.

DESIGN FOR A PANEL.

SPECIFICATION forming part of Design No. 17,115, dated February 15, 1887.

Application filed December 30, 1886. Serial No. 223,056. Term of patent 7 years.

To all whom it may concern:

Be it known that I, FREDERICK MANKEY, of Williamsport, Lycoming county, Pennsylvania, have invented and produced a new and 5 original Design for Panels, of which the following is a specification.

My design consists in the three elongated elevations, A B C, with intermediate channels, D. The edges or sides E of said elevations A B C appear in the form of steps; or, 10 in other words, said elevations have the appearance of a series of superposed elevations of gradually-decreasing area. More than two steps should preferably appear. The accom-

panying photograph, which represents my said 15 design, shows four. The upper surface of said elevations is flat.

I claim—

The design for a panel, substantially as herein shown and described, which consists in the three elongated elevations, A B C, with intermediate channels, D, the sides or edges E of said elevations having the appearance of steps. 20

FREDERICK MANKEY.
